Peter Schlumbohm, 41 Murray St., New York 7, N.Y.;
Francis J. Gorman, executor of said Peter Schlumbohm, deceased

Filed Jan. 17, 1962, Ser. No. 68,349

Term of patent 7 years

(Cl. D62—4)

FIG. 3

FIG. 1

FIG. 2

Fig. 4.

FIG. 1 is a front elevational view of an electric fan showing my new design.

FIG. 2 is a side elevational view of FIG. 1.

FIG. 3 is a plan view of FIG. 1.

FIG. 4 is a rear perspective view of FIG. 1.

The electric cord is fragmentarily shown for convenience of illustration.

The criss-cross shading in the central portion of the article shown in FIG. 1 represents a conventional porous material and it is to be understood that said material continues uniformly throughout said central portion.

I claim:

The ornamental design of an electric fan, as shown and described.
